UNITED STATES PATENT OFFICE.

HARRY S. HART, OF SHREVEPORT, LOUISIANA.

WATCHMAN'S RECORDING MECHANISM.

Application filed June 13, 1921. Serial No. 477,209.

To all whom it may concern:

Be it known that I, HARRY S. HART, a resident of Shreveport, in the parish of Caddo and State of Louisiana, a citizen 5 of the United States, have invented certain new and useful Improvements in Watchmen's Recording Mechanisms, of which the following is a specification.

My invention relates to improvements in 10 watchmen's recording mechanism and the main object of my invention is the provision of a device which will keep a permanent and absolutely correct record of the manœuvres of the watchmen, to indicate that 15 he is performing his service or duty in a reliable and proper manner.

Another object of my invention is the provision of a device capable of production at 20 a very low price to provide a substitute for the expensive and complicated mechanisms at present in use, and which will keep an accurate record as to hour, minute and day of the watchman in order to render it impossible for the watchman to neglect his 25 duty without making such neglect instantly known.

Another object of my invention is the provision of a device of the character and for 30 the purpose stated which will be small and compact in size to occupy a very small space and which can be operated with ease either from within or from the outside, and which in either instance will perform its function in a reliable manner.

Another object of my invention is the provision of a device of the character stated 35 which may be used in connection with an ordinary and cheap clock and which by reason of its few parts will not get out of order and which generally in every particular will provide a desirable, efficient and thoroughly practical device for the purpose intended.

The invention consists of a recording 45 mechanism of the character stated embodying novel features of construction and combination of parts substantially as shown, described and particularly defined by the claim, the right being reserved to make any 50 changes in the structure which come within the scope of the claim.

In order that the details of construction embodied in my invention and its operation 55 may be understood, as well as its many advantages be fully appreciated, I invite atten-

tion to the accompanying drawings, in which:

Figure 1 represents a perspective view of a complete recording mechanism constructed according to my invention, the cover of the 60 case being open to disclose the construction of the encased mechanism.

Figs. 2, 3 and 4 represent on an enlarged scale detail views of the recording dial and 65 associated mechanism, and

Fig. 5 represents a face view of the dial used in my recording mechanism.

Referring by numeral to the drawings, in which the same numbers are used to indicate like parts in all of said views:

The numeral 1 designates a cabinet or case which is of the desired size and provided with a hinged door 2, and a lock 3 of suitable character and having at one end a window 4, to permit observation of the 70 dial of the clock 5, which clock is placed in the casing adjacent one end thereof.

To the head 6 of the minute hand shaft 7, of the clock 5, is connected the inner member of the universal joint or connection 8, 80 while its other member 9, engages the head 10, on the shaft 11, which is connected to operate the gearing 12, which rotates shaft 14, to a speed of one-twelfth of the speed of rotation of said shaft 11, to properly move 85 recording dial 15, which is retained upon its mounting by clamp 13.

To the end of the case above said dial is secured the lug 16, which has pivoted there-to the yoke 17, which is provided with an opening 18, to receive the threaded end 19, of the rod 20, formed at its lower end with a pointer 21, disposed in the slot 22, of the strip 23, secured to or formed integral with said yoke 17, the slot in said yoke being of a length to correspond with the series of circles 23' of the dial, in which circles are placed the days of the week, from Sunday to Saturday, thus permitting the rod with its pointer to be adjusted by means of the nut 24 to travel over the spaces to indicate upon the particular day and the particular hour, as indicated by the numbers 25, on said dial, while said indicating rod is held in its desired adjustment by means of the 105 nut 24.

From the construction described, it will be noted that the mechanism for indicating and recording is connected to and operated by the minute shaft of the clock, and fur- 110

ther that the indicating mechanism is ad-
justed from day to day to record the time
as to the hour and day of the week, and to
operate said indicating and recording mecha-
nism, I provide the yoke 27, which is con-
nected to the indicating rod and has secured
to it at 28 the outer end of the link 29,
whose inner end is connected at 30, to the
lever 31, which is pivoted at 32, to the case,
and by means of the rod 33, said lever may
be moved from the outside, or by means of
the rod 34, said lever may be moved from the
store or inside, which action of either rods
moves the lever upon its pivot, pushing the
indicating rod with its pointer inward to
punch the dial, which is backed by the cork
or like strip 35, which punch mark indi-
cates upon the dial the exact time the watch-
man operates the machine either from within
in or from without, and thus insures the
keeping of an absolutely perfect record and
check upon the watchman to enable a person
to know whether the watchman is per-
forming his duty in a proper manner.
The most important feature of my inven-
tion resides in the fact that the mechanism
is of simple and reliable construction and
can be operated with ease from the minute
and hour shaft of an ordinary clock and

provides an inexpensive device which will 30
perform its functions in an efficient and
practical manner.

I claim:

A mechanism of the character described,
consisting of a case, a clock disposed in one 35
end of said case and having its dial visible
from the outside, a separate recording dial
arranged in the other end of said case and
connected to move with the shaft of said
clock, an adjustable indicating means se- 40
cured to said case and operated manually to
record the day, hour and minute on said re-
cording dial, said means consisting of a rock-
ing lever pivoted to the case, operating rods ex-
tending in opposite directions from the 45
outer ends of said lever, a third rod con-
nected to the said lever and extending in-
ward to move with said rock lever, a rock-
ing frame connected with said rod, a slotted
depending arm, an adjustable indicator 50
mounted in said rocking frame and having
an indenting device passing through said
slotted arm to indicate upon the recording
dial when moved inward by action of said
rocking frame.

In testimony whereof I hereunto affix my
signature.

HARRY S. HART.
